UNITED STATES PATENT OFFICE

HARRY R. PRIEST, OF LOUDONVILLE, OHIO

FOUNTAIN SHAVING BRUSH AND RECEPTACLE

Application filed July 12, 1930. Serial No. 467,606.

This invention relates to shaving brushes and receptacles therefor and has for an object to provide a fountain shaving brush which will be so constructed as to contain shaving cream sufficient for a month more or less of shaving and will be formed of a few parts detachably connected together so as to be easily maintained in a sanitary condition.

10. A further object of the invention is to provide a receptacle for housing the bristles of the brush, said receptacle having a reduced annular neck provided with a wedge surface whereby the shaving brush may be easily slipped into the receptacle and wedged against becoming accidentally dislodged therefrom, said receptacle furthermore having a removable cap opposite the reduced neck provided with a mirror and permitting 15 of the brush being placed upright on the cap to drain after shaving, there being suitable openings arranged in staggered relation in the wall of the cap or receptacle to effectively 20 ventilate the interior so that the bristles will quickly dry out.

With the above and other objects in view the invention consists in certain novel details of construction and combination of parts hereinafter fully described and claimed, it 30 being understood that various modifications may be resorted to within the scope of the appended claims without departing from the spirit or sacrificing any of the advantages of the invention.

35. In the accompanying drawings forming part of this specification,

Figure 1 is a perspective view of the fountain shaving brush and receptacle,

40. Fig. 2 is a longitudinal sectional view through the brush and receptacle showing the magazine extended and containing a full charge of shaving cream, and

Fig. 3 is a cross sectional view through the receptacle.

45. Referring now to the drawings in which like characters of reference designate similar parts in the various views, the fountain shaving brush is shown to comprise a barrel 10 having an axial duct 11 therethrough. The 50 barrel is provided exteriorly at one end with

screw threads 12. At the opposite end the barrel is enlarged to provide a flange coupling 13 which is provided with interior screw threads 14.

A cylindrical magazine 15 is provided with 55 interior screw threads 16 to engage the above mentioned screw threads 12 of the barrel. The magazine is preferably provided in the end wall with an enlarging mirror 27 by means of which portions of the face or even 60 the teeth may be magnified for inspection. The magazine is sufficient in size to receive enough of shaving cream preferably to last thirty days or more, a quarter-turn of the magazine on the barrel being sufficient to supply 65 the brush with an amount of cream suitable for a single shave.

The brush 17 is formed of any suitable bristles which are bound together at the base by a ring 18 which may be formed of hard rubber or any other desired material and the ring 70 is preferably frusto-conical in contour.

For removably attaching the brush to the above mentioned flange coupling 13, a coupling ring 19 is provided with an exteriorly 75 threaded flange 20 to engage the interior screw threads 14 of the flange coupling 13. The ring and flange thereof are frusto-conical in shape so as to conform to the shape of the base ring 18 of the brush and when the ring 80 19 is screwed into the flange coupling 13, the wall of the frusto-conical bore of the ring draws the brush tightly down against the flange coupling 13 and securely anchors the 85 brush in place.

For protecting the bristles against contamination and permitting of the same being dried out thoroughly after each shave, a housing 21 is provided. The housing preferably is cylindrical in contour and is open 90 at both ends. One end of the housing is provided with a reduced neck 22, the bore of which is frusto-conical in shape, that is, it tapers from the inner end 23 to the outer end 24. Furthermore, the reduced neck is preferably recessed, as shown at 25, at the inner end thereof to make the frusto-conical reduced neck of the receptacle yielding or 95 resilient. The fountain shaving brush described above may be slipped through the bore 100

of the receptacle, magazine end first and the flange coupling 13 frictionally wedged within the frusto-conical bore of the reduced neck 22 of the receptacle. To remove the shaving brush, it is simply necessary to push the brush forwardly through the receptacle.

The receptacle 21 is provided with a flanged cap 26 adapted to frictionally engage the wall of the receptacle when applied and thus be secured by the friction between the flange of the cap and the wall of the receptacle against accidental dislodgment. The cap is provided on the outer face with a mirror 27 which is of sufficient diameter to be easily used as a shaving mirror and is preferably counter-sunk in the end wall of the cap so that the receptacle may be stood upright on the cap end, that is, in the reversed position from that shown in Fig. 1, to drain the bristles of the brush.

To effectively dry the bristles after each shaving operation, the wall of the receptacle is provided with staggered openings 28. The interior of the receptacle is ventilated thoroughly through these openings and the bristles are thus effectively dried, should the brush be placed in the receptacle in a wet condition.

The fountain shaving brush may be formed of any desired material which will be strong and durable as well as attractive, and likewise the receptacle 21 and cap 26 may also be formed of any suitable material, although preferably for the sake of attractiveness, the receptacle and cap therefor are formed of transparent material.

It will be pointed out that the flange coupling 13 is of greater diameter than the diameter of the barrel 10 of the fountain shaving brush so that the magazine 15 may be readily advanced up to the coupling so that practically all of the contents of the magazine may be used and thus economy promoted.

Having thus described the invention, I claim:

1. The combination of a shaving brush, and a receptacle adapted to house the bristles, and comprising a cylindrical wall open at both ends and having one end restricted to provide a reduced neck, the bore of said neck being wedge shaped in contour to frictionally engage the shaving brush, there being openings in the receptacle to ventilate the interior thereof, and a cap closing the open end of the receptacle opposite the reduced neck and provided with a mirror in the outer face thereof.

2. The combination of a shaving brush, and a cap for housing the bristles thereof, comprising a cylindrical perforated side wall reduced at one end to provide a reduced neck having a tapered bore adapted to engage the shaving brush, said reduced end of the receptacle being recessed contiguous to the inner end of said bore for promoting resiliency in

said reduced neck, a flanged cap closing said receptacle opposite said reduced neck and provided with a flat end wall, and a mirror countersunk in the outer face of said wall, said cap and mirror forming an extensive base upon which the receptacle may be stood upright with the shaving brush therein to ventilate and drain the bristles of the shaving brush.

3. A fountain shaving brush comprising a barrel having an axial duct therethrough, an interiorly threaded flange coupling on one end of said barrel, the opposite end of said barrel being exteriorly threaded, a magazine having interior screw threads engaging the last named screw threads on said barrel, a brush component comprising bristles bound together at one end by a wedge shaped ring, and a coupling ring threaded into said coupling flange and having a frusto-conical bore engaging said wedge shaped ring and wedging said brush component firmly in place on said barrel.

4. In a fountain shaving brush, a bristle component, a wedge shaped ring surrounding one end of said bristle component, a barrel having an axial duct, a magazine threaded onto said barrel, said barrel terminating opposite the magazine in a flange coupling of greater exterior diameter than the diameter of the barrel, said coupling having interior screw threads, and a coupling ring having external screw threads engaging the screw threads of the coupling and having a bore of substantially frusto-conical contour adapted to engage said wedge-shaped ring and wedge the same securely in place in said flange coupling.

5. A receptacle for shaving brushes comprising a housing of substantially cylindrical contour and terminating at one end in a reduced resilient neck having a wedge shaped annular bore, a cap removably disposed on said wall opposite said neck, and a mirror countersunk in the outer face of said cap and coacting therewith in forming a flat base upon which the receptacle may be stood upright, said receptacle having staggered ventilating openings in the wall thereof.

6. The combination of a shaving brush, and a receptacle adapted to house the bristles, and comprising a cylindrical wall open at both ends and having one end restricted to provide a reduced neck, the bore of said neck being wedge-shaped in contour to frictionally engage the shaving brush, and a cap closing the open end of the receptacle opposite the reduced neck.

7. In a shaving brush, a bristle component, a handle terminating in a flange coupling having interior screw threads, and a coupling ring having external screw threads engaging the screw threads of the flange coupling and having a bore of substantially frusto-conical contour adapted to wedge the

bristle component securely in place in said flange coupling.

8. In a shaving brush, a bristle component, a hollow handle forming a magazine and terminating in a flange coupling having interior screw threads, and a coupling ring having external screw threads engaging the screw threads of the flange coupling and having a bore of substantially frusto-conical contour adapted to wedge the bristle component securely in place in said flange coupling.

In testimony whereof I affix my signature.
